ARM RESTRAINT

John Vernon Neville, Columbus, Mont., assignor
to The Neville-Robinson Company, Duluth,
Minn., a corporation

Application December 30, 1952, Serial No. 22,923

Term of patent 14 years

(Cl. D83—1)

To all whom it may concern:

Be it known that I, John Vernon Neville, a citizen of the United States, residing at Columbus, State of Montana, have invented a new, original, and ornamental Design for Arm Restraint, of which the following is a specification, reference being had to the accompanying drawing, forming a part hereof.

Fig. 1 is a perspective view of an arm restraint, embodying my new design;

Fig. 2 is a plan view of the design;

Fig. 3 is a side elevational view of the design, and

Fig. 4 is an end view of the same.

I claim:

The ornamental design for an arm restraint, as shown.

JOHN VERNON NEVILLE.
